UNITED STATES PATENT OFFICE.

JOSEPH A. IRWIN AND MARY A. IRWIN, OF IUKA, ILLINOIS.

DESIGN FOR A CARPET-STRETCHER.

SPECIFICATION forming part of Design No. 21,674, dated June 28, 1892.

Application filed May 31, 1892. Serial No. 435,085. Term of patent 14 years.

To all whom it may concern:

Be it known that we, JOSEPH A. IRWIN and MARY A. IRWIN, of the city of Iuka, Marion county, and State of Illinois, have invented 5 a new and original Design for a Carpet-Stretcher, of which the following is a full, clear, and exact description, reference being had to the accompanying drawings, forming a part hereof.

10 Figure 1 is a side elevation of a carpet-stretcher embodying our design, and Fig. 2 is an end elevation of the same.

The leading feature of our design is the substantially rectangular body 1, having beneath it and extending longitudinally of it a series of parallel projections 2, all substantially similar in contour, each having one side inclined and the opposite side perpendicular and each converging downwardly and terminating in an attenuated apex. The opposite ends 3 of the body 1 have plain surfaces. The opposite vertical edges of the body 1 are each provided with a raised panel 4, having chamfered marginal edges 5, and each panel pro-

vided on its outer face with a series of small 25 circles 6, arranged in a horizontal line. The upper surface of the body 1 is provided with a rounded apical rib 7, which extends longitudinally thereof and parallel to the series of projections 2. On either side of the apical 30 rib 7 is a longitudinally-extending depression 8, the walls whereof are located in a plane below the apex of the rib 7. Projecting at an angle from the rectangular body of the article and intercepting the rib 7 and the depression 8 on one side of said rib is a cylindrical elongated body 9, having its free end 10 bent downwardly.

What we claim is—

15 The design for a carpet-stretcher, as herein shown and described.

In testimony whereof we affix our signatures in presence of two witnesses.

JOSEPH A. IRWIN.
MARY A. IRWIN.
